Primary Examiner—Lisa Lichtenstein(74) *Attorney, Agent, or Firm*—Panitch Schwarze Belisario & Nadel LLP(57) **CLAIM**

The ornamental design for an electric evaporator device, as shown and described.

DESCRIPTION

FIG. 1 is a right side and front perspective view of an electric evaporator device showing our new design;

FIG. 2 is a right side view thereof;

FIG. 3 is a front view thereof;

FIG. 4 is a rear view thereof;

FIG. 5 is a top plan view thereof; and,

FIG. 6 is a bottom plan view thereof.

The broken [line showing of environment structure in FIGS. 1, 2, and 4-6, is] lines in the figures are for illustrative purposes only and [forms] form no part of the claimed design.

1 Claim, 2 Drawing Sheets

Matter enclosed in heavy brackets [ ] appears in the original patent, but forms no part of this reissue; matter printed in italics indicates the additions made by reissue.
